United States Patent Office

Des. 228,446
Patented Sept. 25, 1973

228,446

END CUSHIONING COVER FOR PACKAGES OR THE LIKE

Anthony N. Paone, Syracuse, N.Y., assignor to
SCM Corporation

Filed Dec. 13, 1971, Ser. No. 207,711

Term of patent 14 years

Int. Cl. D9—03

U.S. Cl. D9—254

FIG. 1 is a perspective view of an end cushioning cover for packages or the like showing my new design;
 FIG. 2 is an end elevational view;
 FIG. 3 is a top plan view;
 FIG. 4 is a front elevational view;
 FIG. 5 is a bottom plan view; and
 FIG. 6 is a rear elevational view.

I claim:
 The ornamental design for an end cushioning cover for packages or the like, substantially as shown.
